HEATING APPARATUS

Bernard Goerg, Scarsdale, N. Y., assignor, by
mesne assignments, to American Radiator &
Standard Sanitary Corporation, New York,
N. Y., a corporation of Delaware

Application February 19, 1938, Serial No. 191,373

7 Claims. (Cl. 237—1)

My invention relates to heating apparatus, and more particularly to that type which has to do with the heating of room spaces of building structures.

5 The invention consists in the novel construction and combination of parts, to be more fully described hereinafter, and the novelty of which will be particularly pointed out and distinctly claimed.

10 In the accompanying drawings, to be taken as a part of this specification, I have fully and clearly illustrated a preferred embodiment of my invention, in which drawings—

15 Fig. 1 is a fragmentary vertical sectional view showing a building structure with my improved form of heating apparatus forming a part thereof;

20 Fig. 2 is a fragmentary vertical sectional view taken on the line 2—2 of Fig. 1, with parts being broken away to illustrate more clearly certain of 25 the detail features of my improvement;

Fig. 3 is a fragmentary horizontal section taken on the line 3—3 of Fig. 2;

25 Fig. 4 is a detail view illustrating partly in side elevation and partly in vertical longitudinal section one form of a tubular heating element forming a part of my improvement;

Fig. 5 is a vertical section of the tubular heating element shown in Fig. 4, the view being taken on the line 5—5 of Fig. 4; and

30 Fig. 6 is a fragmentary perspective view, partly in section, showing another form of heating element used in my improved heating apparatus.

Referring now in detail to the construction illustrated and first to Figs. 1, 2 and 3, it will 35 be observed that I have shown my invention as embodied in a building structure indicated in general by the reference character 10. In so far as the present invention is concerned, the building 10 may be of any suitable type and 40 size. The building structure shown in the drawings is of the one-story frame type and comprises a basement space 11, an attic space 12 and one or more room spaces. In the drawings, I have shown two room spaces 13 and 14. The 45 room space 13 is defined by a floor 15, a ceiling 16 and four upright side walls. Only three of the side walls appear on the drawings and they are indicated, respectively, by the reference character 17, 18 and 19. The side wall 17 forms a 50 part of the outside side wall of the building and the side wall 18 functions as an inside or partition wall dividing the room spaces 13 and 14. One of the other defining side walls of the room space 14 is indicated at 20.

55 The inside partition wall 18 is here shown as

being composed of upright spaced substantially parallel wall members 21 and 22, which define therebetween a closed air space 23. Each of the wall members 21 and 22 is shown as being formed of a conventional type of metal lath 24 to which 5 is applied a covering of plaster 25. The lower parts of the wall members 21 and 22 terminate short of the floor to provide openings 26 and 27, respectively, and these openings are closed by baseboard members 28 and 29.

10 The air space 23 is closed at its upper side by an upper closure member or partition cap 33, which extends entirely across the upper part of the partition wall, as shown. The lower part of the air space 23 is closed by a lower closure 15 member 34, commonly referred to as a shoe or sole piece. The shoe piece 34 extends entirely across the lower end of the partition wall. The air space 23 is divided vertically into a plurality of sections 35 by the usual studs 36 equally spaced 20 apart and arranged between the partition cap 33 and shoe piece 34 and between the inside surfaces of the wall members 21 and 22. The studs 36 serve to space the wall members 21 and 22 apart and to separate the several sections 35 25 from the other.

Arranged within each of the sections 35 of the air space 23 is a partition 38 which extends in the same general direction as the plane of the partition wall and which is spaced from the 30 inside surfaces of the wall members 21 and 22 to provide parallel upgoing and downcoming passages 40 and 41, respectively. The partitions 38 terminate at their upper and lower ends short of the partition cap 33 and shoe piece 34, respectively, to provide communication between the upgoing and downcoming passages 40 and 41 of their respective sections 35 at the upper and lower ends of such passages.

35 The upright longitudinal edges of the partitions 40 38 are secured, respectively, to the adjacent faces of the studs 36 by any suitable means, such, for example, as nails 43. In so far as certain aspects of the present invention are concerned, the partitions 38 may be formed of any suitable material. Preferably, the partitions are formed of an inexpensive material which can be easily and quickly sized and installed. The partitions 38 shown in the drawings are formed of corrugated 45 paper board.

40 Arranged, respectively, within the lower parts of each of the sections 35 and at the lower ends of the downcoming and upgoing passages thereof, are heating devices 44. The heating devices 45 may be installed in their several sections through 50 55

either the opening 26 or the opening 27, previously referred to, and when installed, the opening selected is closed by its respective baseboard member. In certain installations it may be found that the openings 26 and 27 are not necessary. In such case, the walls 21 and 22 will extend to the floor.

In so far as the broader aspects of the present invention are concerned, the heating devices 44 may be of any suitable kind or type. In the drawings, I have shown the heating devices as preferably comprising tubular heat exchange elements which are connected together for series flow of heating fluid therethrough by short connecting pipes 45. Where necessary, the studs 38 may be notched to receive the pipes 45. The elements 44 may be connected by supply and return pipes 46 and 47 into a conventional type of heating apparatus; for example, a steam or hot water boiler (not shown).

Each of the tubular heat exchange elements 44 is shown as comprising an integral cast-metal hollow body 50 which is L-shaped in vertical cross-section (see also Figs. 4 and 5). Each of the heat exchange elements is shown as being provided with extended external heating surface in the form of fins 51 cast integral with its hollow body 50. The heat exchange elements 44 are shown as being arranged in their respective sections 35 with their horizontal legs extending across the lower ends of the passages 40 and 41 and with their vertical legs extending upwardly into the upgoing passage 40. The purpose of this arrangement is to provide more external heating surface in the upgoing passages 40 than in the downcoming passages 41, so that the air within each section 35 will circulate continuously therethrough by gravity, the air flowing upwardly from the elements 44 through the passages 40 and then downwardly through the passages 41 to the elements 44. The fins 51 are so arranged that they extend in the general direction of flow of the air so as to offer the minimum of resistance to such flow.

With the construction thus far described and with a heating fluid, such as steam or hot water, supplied to the heat exchange elements 44, the wall members 21 and 22 will become heated as the air flows continuously by gravity over the heat exchange elements and along the inside surfaces of such wall members. When the wall members 21 and 22 become heated, such heat will be transmitted to the room spaces 13 and 14 and to the occupants therein, largely by radiation. For this reason, the temperature of the room spaces 13 and 14 may be carried at a substantially lower value than is possible with the prior art heating systems, and the occupants of the room spaces will feel comfortable at all times. For example, in a room heated mainly by convection air currents flowing over a radiator or other source of heat and around the interior of the room, it is necessary for comfort to maintain the temperature of the room between 70° and 73° F.; but in a room heated by the structural arrangement described herein, which is largely by radiation from the walls, the occupants of the room spaces will be comfortable at lower temperatures, such for example, as 65°. For this reason, by the use of my improved construction, room spaces can be heated with a substantially less amount of fuel than is possible with the prior art structures. Furthermore, as the entire side wall 18 is heated, the temperature of the rooms will be maintained at a relatively even value, and there will be little

or no cold draft condition adjacent to the floor, such as is common with some convection heating systems when there are off-periods when no heat is supplied to the room from the source of heat. Another advantage of the present construction is that the heat is not cut off suddenly from the room during off periods. This is because the relatively heavy walls 21 and 22 lose their heat slowly, thereby maintaining convection circulation along their surfaces and preventing stratification and cold floors.

So far, I have described an improved form of apparatus for heating adjoining rooms 13 and 14 by radiation from their common dividing or partition wall 18. In accordance with the present invention, other side walls of the rooms may also be heated by apparatus similar to that already described. It will be appreciated that the number of side walls heated or the number of heated sections of the closed air space in a given side wall will depend upon the prevailing weather conditions where the house is located, the particular location of the room to be heated, and the structural details of the building. In the drawings, I have shown the outer side wall 17 of the room space 13 as being heated in the same manner as the partition wall 18.

The outer side wall 17 of the room is shown as being provided with a closed air space 23a and as being heated by the circulation of heated air 30 in such closed air space. The wall 17 is shown in Fig. 1 as being composed of an outside wall member 60 and an inside wall member 61 arranged in spaced substantially parallel relation with respect to one another so as to provide the 35 closed air space 23a. The upper part of the air space 23a is closed by an upper closure member or plate 33a extending thereacross, and the lower part of the space 23a is closed by a shoe or sole piece 34a also extending thereacross. Arranged between the plate 33a and sole piece 34a and between the inside surfaces of the wall members 60 and 61 are a series of spaced vertical studs 36a (only one being shown) which close the upright sides of the air space and divide the latter into 40 sections 35a (only one shown) in the same manner as the studs 36 of the partition wall 18.

The outer wall member 60 is here shown as being composed of the usual sheathing 63, to the exterior of which is applied siding 64. The inside surface of this outer wall 60 is shown as being lined with a heat-insulating material 65, so as to prevent the loss of heat to the outside atmosphere. In so far as the present invention is concerned, the insulating material 65 may be of any suitable type. In the drawings, I have shown the material 65 as being preferably composed of a plurality of layers of corrugated paper or sheet asbestos 66, to the inside surface of which is applied a covering of aluminum foil 67, the latter 60 functioning to reflect the heat back towards the room space 13.

The inside wall member 61 is shown as being composed of metal lath 24a to which is applied the plaster 25a. The sections 35a of the air space 65 23a are divided, respectively, by upright partitions 38a (only one shown) into upgoing passages 40a extending along the inside surface of the wall member 61 and into downcoming passages 41a extending along the inside surfaces 70 provided by the aluminum foil 67. The upright partitions 38a are of the same construction and are arranged with respect to their adjacent wall surfaces in the same manner as the partitions 38 of the previously described partition wall 18. The 75

partitions 38a terminate short of the plate 33a and sole piece 34a to provide communication between the passages 40a and 41a of each section at the upper and lower ends, respectively, of such passages.

Arranged, respectively, within the lower parts of the upgoing passages 40a of the sections 35a are tubular heat exchange elements 44a. As shown in Figs. 1 and 6, the elements 44a are of slightly different construction from the elements 44 of the partition wall 18. Each of the elements 44a comprises an integral cast-metal hollow body member 50a on which is formed integral cast-metal fins 51a arranged in parallel relation and extending in the general direction of flow of the air through the passages 40a and 41a. The elements 44a are arranged within the lower ends of their respective upgoing passages 40a. The elements 44a do not extend across the down-coming passages because they only serve to keep warm the inside wall member 21; whereas, the heat exchangers 44 of the partition wall 18 keep warm both the wall member 21 and the wall member 22. It is to be noted that the purpose of the heating elements 44a in the outside wall 17 is not so much to transmit heat to the room space as it is to prevent heat loss from the room space to the outside atmosphere. Consequently, the temperature of the outside wall is kept above the room temperature, but is not kept as high as the partition wall 18. Therefore, less heat is required, and the heating element 44a can be smaller.

It will be appreciated that the heat exchange elements 44a are arranged across their respective sections 35a of the wall 17 and are connected together in series and to the supply and return mains of a heating system in the same manner as the heat exchange elements 44 of the wall 18. The inside wall member 21 terminates short of the floor 15 to provide openings 27a in the several sections 35, through which the heat exchange elements 44a may be inserted when installed. When the partitions 38a and heat exchange elements 44a are installed, the openings 27a are closed by a baseboard member 29a so that there will be little or no air leak between the air space 23a and the room space 13.

From the above, it will be apparent that I have shown apparatus for heating room spaces of building structures by radiation, which apparatus is very simple and can be readily installed with only slight changes in conventional building structures. For this reason, the apparatus can be readily embodied either in existing building structures or in new structures. Side walls of room spaces in buildings are usually formed by spaced wall members, partition caps, sole pieces, baseboards and vertical studs as described above. As this is true, all that need be done in order to apply the present invention to an existing building is to remove one of the side wall members, cut the partition to proper size, install the partitions between the studs, and insert and connect the heat exchange devices into the existing heating system. In installing my apparatus in an outside wall of a building, the procedure outlined above will also be followed, with the addition that a lining of heat insulating material, such as is indicated at 65, will be applied to the inside surface of the outside wall member.

As stated above, by reason of the fact that the room is heated mostly by radiation, a comfortable and more even temperature can be maintained within the room at a lower operating cost than

by prior systems relying mainly on convection air currents in the room. I am aware that I am not the first to heat room spaces by circulating warm air through the hollow defining walls thereof and transferring the heat from the warm air to the occupants of the room by radiation. However, the novel structural arrangement disclosed above is believed to be more simple, more compact, more effective and capable of being more readily installed with fewer changes in building structures, than the structures of this type previously known.

What I claim and desire to secure by Letters Patent of the United States is as follows:

1. In heating apparatus, the combination of an upright defining side wall for a room comprising a pair of upright side wall members arranged in spaced substantially parallel relation and defining a closed air space therebetween, upper and lower members closing the upper and lower sides of said air space and upright spacing members extending between the side wall members and closing the upright sides of said air space; an upright partition arranged within said air space and in spaced relation with respect to the inside surfaces of said side wall members to define therewith an upgoing passage along the inside surface of one side wall member and a downcoming passage along the inside surface of the other of said side wall members; said partition terminating short of said upper and lower members to provide communication between the passages at their upper and lower ends; a tubular heating element arranged in the lower end of said upgoing passage and in the lower end of said downcoming passage and being so constructed that a larger external heating surface is provided in the upgoing passage than is provided in the downcoming passage; and means for supplying a heating fluid to said heating element.

2. In heating apparatus, the combination of an upright defining side wall for a room comprising a pair of upright side wall members arranged in spaced substantially parallel relation and defining a closed air space therebetween, upper and lower members closing the upper and lower sides of said air space and upright spacing members extending between the side wall members and closing the upright sides of said air space; an upright partition arranged within said air space and in spaced relation with respect to the inside surfaces of said side wall members to define therewith an upgoing passage along the inside surface of one side wall member and a downcoming passage along the inside surface of said other side wall member; said partition terminating short of said upper and lower members to provide communication between the passages at their upper and lower ends; and a tubular heating element arranged within the lower part of said air space and extending in the general direction of said side wall and between the inside surfaces of the spacing members; said tubular heating element being L-shaped in vertical cross-section and arranged with its horizontal leg at the lower ends of both said upgoing and said downcoming passages and with its vertical leg arranged in said upgoing passage; and means for supplying a heating fluid to said heating element.

3. Heating apparatus for a room comprising an upright hollow side wall extending along one side of the room and between the floor and ceiling thereof and being composed of parallel inner and outer wall members spaced from one another to define an air space therebetween; a bottom

closure member extending across the lower part of said side wall at the floor level and closing the lower part of said air space; a top closure member extending across the upper part of said side wall at the ceiling level and closing the upper part of said air space; an upright partition arranged within said air space and in the general plane of said side wall and being spaced from the inner and outer wall members to define there-
with parallel upgoing and downcoming passages, respectively, connected at their lower and upper ends to provide for continuous circulation of air through said space; and a tubular heating device arranged within the lower end of said upgoing air space and adapted to be supplied with a heating fluid.

4. Heating apparatus for a room comprising an upright hollow side wall extending along one side of the room and between the floor and ceiling thereof and being composed of parallel inner and outer wall members spaced from one another to define an air space therebetween; a bottom closure member extending across the lower part of said side wall adjacent the level of the floor and closing the lower part of said air space; a top closure member extending across the upper part of said side wall and adjacent the level of the ceiling and closing the upper part of said air space; an upright partition arranged within said air space and in the general plane of said side wall and being spaced from the inner and outer wall members to define therewith parallel upgoing and downcoming passages, respectively, connected at their lower and upper ends to provide for continuous circulation of air through said space; a tubular heating device arranged within the lower end of said upgoing air space and adapted to be supplied with a heating fluid; the lower part of said inner wall member having an opening there-
in providing access to said heating device; and a baseboard member normally closing said opening.

5. Heating apparatus for a room comprising an upright hollow side wall extending along one side of the room and between the floor and ceiling thereof and being composed of parallel inner and outer wall members spaced from one another to define an air space therebetween; a bottom beam member extending across the lower part of said side wall adjacent the level of the floor and closing the lower part of said air space; a top beam member extending across the upper part of said side wall and adjacent the ceiling level and closing the upper part of said air space; a pair of spaced upright studs arranged between the inner and outer members and extending between the two beam members and providing side closures for said air space; an upright partition arranged within said air space between studs and spaced from the inner surfaces of the inner and outer wall members to divide said air space into upgoing and downcoming passages, respectively, connected at their lower and upper ends to provide for continuous circulation of air through

said air space; and a tubular heating device arranged in the lower end of said upgoing passage and adapted to be supplied with a heating fluid.

6. Heating apparatus for a room comprising an upright hollow side wall extending along one side of the room and between the floor and ceiling thereof and being composed of parallel inner and outer wall members spaced from one another to define an air space therebetween; a bottom beam member extending across the lower part of said side wall adjacent the level of the floor and closing the lower part of said air space; a top beam member extending across the upper part of said side wall and adjacent the ceiling level and closing the upper part of said air space; a pair of spaced upright studs arranged between the inner and outer members and extending between the two beam members and providing side closure members for said air space; an upright partition arranged within said air space between studs and spaced from the inner surfaces of the inner and outer wall members to divide said air space into upgoing and downcoming passages, respectively, connected at their lower and upper ends to provide for continuous circulation of air through said air space; a tubular heating device arranged in the lower end of said upgoing passage and adapted to be supplied with a heating fluid; said inner wall member having an opening therein adjacent the lower part of said air space and providing communication with said heating device; and a baseboard member normally closing said opening.

7. Heating apparatus for a room comprising an upright hollow side wall extending along one side of said room and between the floor and ceiling thereof and being composed of parallel inner and outer wall members spaced from one another to define an air space therebetween; a bottom beam member extending across the lower part of said side wall adjacent the level of the floor and closing the lower part of said air space; a top beam member extending across the upper part of said side wall and adjacent the level of the ceiling and closing the upper part of said air space; a plurality of upright spaced studs resting at their lower ends on the bottom beam member and supporting by their upper ends the top beam member and dividing the air space into a plurality of side-by-side sections; an upright partition within each section and between adjacent pairs of studs and dividing its respective section into upgoing and downcoming passages, respectively, connected at their upper and lower ends to provide for continuous circulation of air; a tubular heating device arranged in the lower end of the upgoing passage of each section and adapted to be supplied with a heating fluid; the lower part of said inner wall member having an opening providing access to said heating device; and a baseboard member normally closing said opening.

BERNARD GOERG.
